SANDING AND POLISHING MACHINE FOR WORKING ON CURVED AND SHAPED PROFILE PIECES

Ettore Vichi, Pesaro, Italy

Filed Nov. 2, 1959, Ser. No. 850,123

Claims priority, application Italy Nov. 12, 1958
3 Claims. (Cl. 51—101)

The present invention relates to an automatic sanding and polishing machine with a template, a follower and a revolving working table suited to the working of curved and shaped profile-pieces characterized in that the arm carrying the sanding or polishing roller is disposed perpendicular to the revolving working table to which the template and the pieces to be worked are fixed.

For better illustration the accompanying drawings show in FIG. 1 a perspective view of a preferred embodiment of the machine according to the invention; in FIG. 2 a side view of the same machine; in FIG. 3 a front view of the same machine; in FIG. 4 a perspective view of a second embodiment of the machine according to the invention.

Referring now to the FIGS. 1, 2, and 3, 1 indicates the fork-shaped arm, the ends of which carry by means of brushings or bearings the shaft 2 carrying the sanding roller or the polishing felts 3. The arm 1 is mounted on the base 4 of the machine by means of the tie-rod 5 and revolves thereabout. The torsion spring 6 is compressed in such a way as to urge the sanding roller or the polishing felts against the pieces to be worked mounted on the revolving working table 7. The motor 8, mounted on the upper arm of the fork 1 sets through belts or chains the shaft 2 into rotation which carries the sanding roller or the polishing felts 3. The motor 9 placed in the inside of the base 4 of the machine transmits the motion to the working turn table 7.

The sense of rotation of the motor 8 and therefore of the shaft 2 carrying the sanding rollers 3 is opposite to the one of motor 9 transmitting the rotation to the table 7.

If now on the working turn table 7 a template 10 is applied the shape of which is equal to the shape of the pieces to be worked, the copying follower 11 (that is also mounted on shaft 2 carrying roller 3) will always be pressed against the template 10, due to the action of the spring 6, to closely and constantly follow its profile.

It results obviously that also roller 3 will follow the form of the pieces to be worked as these have the same profile as template 10.

The handwheel 12 holds shaft 2 in place thus permitting the replacement of the rollers 3.

The base 4 is made of heavy material for decreasing the vibration of the machine and to guarantee more stability.

The transmission system between the motor and the shaft carrying the roller, between the motor and the turn table, as well as the form of the arm and of the base of the machine may be chosen at will without however departing from the spirit of the invention.

FIG. 4 shows a variant of the invention that provides better performance, still having however the same basic characteristics as those outlined in FIGS. 1-3.

The machine of FIG. 4 has the additional characteristic that the follower and the sanding or polishing roller are allowed to approach or to withdraw from the revolving turn table and therefore from the pieces to be worked and from their form.

This characteristic allows performing operations of details of small or large dimensions.

While in the machine of FIGS. 1, 2 and 3 the possibili-

2

ties of operations are limited as the arm 1 carrying the roller 3 may only effect a limited rotation and therefore cover a reduced range of operation, with the machine of FIG. 4 the possibilities of operation are much larger.

5 With reference to FIG. 4, 4 indicates the base and the main body of the machine that is crossed by the slide 22 displaceable by means of the rack 23 actuated by hand-wheel 24.

One end of the slide 22 has a pivot 15 to which the arm 16 carrying the follower 11 and its registering member 18 as well as the shaft 2 bearing the sanding roller and the polishing felts 3 is pivoted.

The casing 21 contains the electric motor that sets the shaft 2 and therefore the roller 3 into rotation. The spring 32, the tension of which is regulated by means of bushings or bearings the shaft 2 carrying the sanding roller or the polishing felt 3 together with the follower 11 against the pieces to be worked placed on the revolving working table or platform 7. This platform or table 20 mounted on the main base 4 of the machine is set into rotation (in the opposite sense as the motor actuating the shaft 2) by means of the variable speed motor 25.

As already mentioned in connection with the description relating to FIGS. 1, 2 and 3 the revolving working table 7 carries a template 10 equal in shape to the pieces to be worked and made to continuously bear against the follower 11.

It is therefore obvious that the possibility of moving the slide 22 through the base of the machine permits one to effect operations on details of small and large dimensions, which are not possible to perform with the machine of FIGS. 1, 2 and 3.

The dimensions of the slide and the means for obtaining the longitudinal displacement of the slide 22 may be 35 of course chosen at will without departing from the spirit of the present invention.

What I claim is:

1. An automatic sanding and polishing machine for 40 working on curved pieces and shaped profile pieces, comprising a base, a turntable mounted in said base for supporting the piece to be worked, a template mounted on said turntable for defining the configuration the piece to be worked obtains, motive means to rotate said turntable and said template about an axis in one direction, a 45 movable slide mounted in said base perpendicular to the axis of rotation of said turntable and said template, means to longitudinally displace said slide relative to said base, an arm having one end pivotally mounted to one end of said slide, biasing means mounted on said slide adjacent 50 said arm for urging said arm toward said base, a shaft vertically mounted on the other end of said arm, a work-performing member mounted on said shaft, means to rotate said shaft and work-performing member in a direction opposite to that of said turntable and template, 55 and a cone-shaped follower member mounted on said shaft for riding against said template to adjust the wear on said work-performing member.

2. A machine according to claim 1 in which said 60 means to longitudinally displace said slide consists of a rack operated by a handwheel.

3. A machine according to claim 1 in which said biasing means consists of a spring, the tension of which is regulated by a handwheel.
